ATTORNEY

UNITED STATES PATENT OFFICE.

LOUIS B. HARVEY, OF STOCKTON, CALIFORNIA, ASSIGNEE TO HARVEY RIM & WHEEL COMPANY, INC., OF BUFFALO, NEW YORK.

DRIVING-ARCH FOR WHEEL-FELLIES.

1,389,139.

Specification of Letters Patent Patented Aug. 30, 1921.

Application filed March 6, 1920. Serial No. 364,163.

To all whom it may concern:

Be it known that I, Louis B. HARVEY, a citizen of the United States, residing at Stockton, in the county of San Joaquin, State of California, have invented certain new and useful Improvements in Driving-Arches for Wheel-Fellies; and I do declare the following to be a full, clear, and exact description of the same, reference being had to the accompanying drawings, and to the characters of reference marked thereon, which form a part of this application.

This invention relates to improvements in a driving means between a demountable rim and the fixed rim of the wheel, the principal object of the invention being to provide a means which will successfully permit of the use of demountable rims with disk wheels.

This driving lug is particularly adapted to be used with a fixed rim of the type shown in my co-pending application for patent filed March 8, 1920, Serial No. 364,162, and with a demountable rim of the type shown in my co-pending application for sectional rim filed March 25th, 1919, Serial No. 284,983.

Another object is to so construct and position this driving arch that it may be used in connection with the bolt which I use to bind the parts of my sectional rim together, without the need of adding other parts to the rim, and thus permitting this bolt or lug to serve a double purpose.

A further object of the invention is to produce a simple and inexpensive device, and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Figure 1 is a fragmentary longitudinal section of a fixed rim and demountable rim, showing the driving arch installed.

Fig. 2 is a cross section on a line 2—2 of Fig. 1.

Fig. 3 is a cross section of the entire fixed rim and demountable rim, showing the method of removing the rim to disengage it from the driving arch.

Referring now more particularly to the characters of reference on the drawings, the

numeral 1 denotes the fixed rim, which is preferably channel shaped, having annular sides or flanges 2 and 3, the inner one 2 of which has an internal peripheral groove or seat 4 adapted to receive the inner edge of a flange 5 depending from the rim 6.

This rim is formed of a plurality of segmental parts, as fully set forth in the application hereinbefore mentioned, adjacent the end of one of which parts 6^a is a radially positioned stud bolt 7, projecting inwardly. A plate 8 passes over the stud and overlaps the end of the rim-segment 6^a which abuts against the segment 6^a.

A sleeve-nut 9 screws over the stud and bears against the plate 8.

At any suitable point in the fixed rim 1 between the flanges thereof is fixed an arch shaped member 10, extending circumferentially of said fixed rim and being provided with an orifice 11 to receive the inner end of the sleeve member 9 therein.

This arch is so proportioned and shaped relative to the position of the sleeve nut, that the metal thereof will bear against said sleeve as close to the rim as possible, so as to reduce the tendency of the stud to bend under a driving strain.

A locking ring 12 is removably fixed to the outer flange 3, and is adapted to receive the outer rim-flange 13.

Thus it will be seen that regardless of the tightness of the locking ring, the rim cannot turn relative to the fixed rim.

In order to remove the rim, the locking ring 12 is first removed, and the rim then pulled outwardly at a point opposite to the arch 10. This clears the rim from contact with the fixed rim at that point, and it may then be moved radially so that the sleeve 9 will clear the arch 10.

From the foregoing description it will be readily seen that I have produced such a device as substantially fulfills the object of the invention as set forth herein.

While this specification sets forth in detail the present and preferred construction of the device still in practice such deviations from such detail may be resorted to as do not form a departure from the spirit of the invention, as defined by the appended claims.

Having thus described my invention what I claim as new and useful and desire to secure by Letters Patent, is:—

1. In combination with a sectional rim having a stud on one end of a section and a nut on the stud arranged in connection with a plate to lock adjacent ends of the sections against radial movement, a sleeve extension formed with the nut, the fixed rim of the wheel being provided with an orificed member to receive the said extension.
2. In combination with a demountable rim, 10 a radial stud thereon, a sleeve threaded onto the stud, and a driving arch carried by the
- fixed rim of the wheel and provided with an orifice into which the sleeve projects.
3. In combination with a sectional rim, a stud on one end of a section, and a nut on the 15 stud arranged in connection with a plate to lock adjacent ends of the sections against radial movement, the fixed rim of the wheel being provided with an orifice to receive the nut therein. 20

In testimony whereof I affix my signature.
LOUIS B. HARVEY.
